(57) CLAIM

The ornamental design for a seat, as shown and described.

DESCRIPTION

FIG. 1 is a perspective view of a seat showing my new design;

FIG. 2 is a front view thereof;

FIG. 3 is a side elevational view, the opposite side being a mirror image thereof; and,

FIG. 4 is a rear elevational view thereof.

The views of the seat not shown form no part of the claimed design. The broken lines depicting back ornamentation represent environmental elements only and form no part of the claimed design.

1 Claim, 4 Drawing Sheets
